UNITED STATES PATENT OFFICE.

JOSEPH SILVERMAN, OF CHICAGO, ILLINOIS.

DESIGN FOR A BENT-WOOD CHAIR.

52,083.

Specification for Design.

Patented June 4, 1918.

Application filed March 26, 1918. Serial No. 224,903. Term of patent 14 years.

To all whom it may concern:

Be it known that I, JOSEPH SILVERMAN, a citizen of the United States, residing at Chicago, in the county of Cook and State of Illinois, have invented a new, original, and ornamental Design for Bent-Wood Chairs, of which the following is a specification, reference being had to the accompanying drawings, forming a part thereof.

Figure 1 is a front elevation, and Fig. 2 is a plan view of a chair embodying my design.

I claim—

The ornamental design for a bent wood chair, as shown.

JOSEPH SILVERMAN.
